[57] **CLAIM**

The ornamental design for a fluid nozzle, as shown and
described.

DESCRIPTION

FIG. 1 is a front perspective view of the fluid nozzle of
the present invention;

FIG. 2 is a left-side elevational view of the fluid nozzle
of FIG. 1;

FIG. 3 is a rear perspective view of the fluid nozzle of
FIG. 1;

FIG. 4 is a right-side elevational view of the fluid nozzle
of FIG. 1;

FIG. 5 is a front elevational view of the fluid nozzle of
FIG. 1; and,

FIG. 6 is a rear elevational view of the fluid nozzle of
FIG. 1.
